UNITED STATES PATENT OFFICE.

BENJAMIN HOWARD DAVIS, OF BOSTON, MASSACHUSETTS.

REINFORCED AND SAFETY SEALED-BOX CONSTRUCTION AND METHOD OF MANUFACTURING.

Application filed November 25, 1921. Serial No. 517,638.

To all whom it may concern:

Be it known that I, BENJAMIN HOWARD DAVIS, a citizen of the United States, and resident of Boston, in the county of Suffolk and State of Massachusetts, have invented an Improvement in Reinforced and Safety Sealed-Box Constructions and Methods of Manufacturing, of which the following description, in connection with the accompanying drawings, is a specification, like letters on the drawings representing like parts.

My present invention is directed to a reinforcing and safety sealing construction for boxes, packing cases, and packages, wherein it is important to have a strong construction substantially pilferage proof, as well, also, as to provide a means of insuring the construction against damage by removal of a section, board or portion, tampering with the contents, and thus to prevent thieving during transit.

It is also an important feature of my present invention that I provide a combined reinforcing and safety sealing means. In other words I have not only devised a seal, or sealing and indicating construction which will at once be an indicator if the box has been tampered with, as well, also, as to provide such sealing construction of strong, firm arrangement to prevent any successful tampering therewith. Heretofore I believe that it has been customary to have a sealing device simply and solely as an indicator to show at once whether the seal has been broken and the contents of the article sealed interfered with, the strengthening and reinforcing feature being a separate and independent item of construction. My invention combines these both in a single member, and this feature I wish to claim broadly.

A further important novelty in my present invention consists in the arrangement of reinforcing and strengthening straps and devices positioned on the interior of the box and thus substantially free from danger of damage, removal or tampering after the box is closed and ready for shipment. This method of box construction effectually prevents the common method of pilfering from packing cases, which has consisted in hammering out one of the planks or boards of which the packing case may be built, removing the contents or some of them, and

replacing the board so as to prevent notice. By the interior strap arrangement and attachment therefor, I effectually prevent such a method of damage. A further and very important novel feature consists in my invention whereby a portion of the reinforcing straps project through from inside to outside or vice versa, substantially encircling the corner, edge or cover and sides of the box. I am advised that this feature, whereby a metallic reinforcing, sealing, strengthening and protecting member is bent over the corner or combining the cover and box construction at a corner, is new, and I therefore wish to claim this feature broadly, as well as in combination with the various other novelties of my invention. A still further advantage of my present invention resides in the concealed manner in which the reinforcing, strengthening and safety means are secured. I not only provide a strengthening construction which will also effectually and positively prevent pilfering, unless the entire box is demolished, but I have devised means to secure the ends of the reinforcing, sealing and strengthening members, in a protected manner, difficult to be discerned by an outsider and impossible of ready removal, while yet permitting the box to be opened by one knowing the method and arrangement, and thus to preserve the case for future and further use.

Further features, important advantages and novel combinations of parts will be hereinafter more fully pointed out and claimed.

Referring to the drawings, illustrating a preferred embodiment of my invention, showing a box construction carrying out my method, and illustrating the numerous novel features above briefly outlined:

Fig. 1 is a general perspective view;

Fig. 2 is also a fragmentary view showing process of construction;

Fig. 3 is a fragmentary cross-sectional view showing a perforation through the box cover for the insertion of the reinforcing member;

Fig. 4 illustrates same in position;

Fig. 5 shows the next step after Fig. 4 in the process of assembling;

Fig. 6 illustrates the next succeeding step;

Fig. 7 shows a further step in the process or method of construction;

Fig. 8 illustrates the pliant and concealed fastening on the line 8—8 of Fig. 7;

Fig. 9 is a fragmentary cross-sectional view on the line 9—9 of Fig. 8; and

Fig. 10 shows a type of device suitable for use in carrying out my method.

My invention is applicable to box construction of any size desired, affording equal advantages to small, compact boxes, such for example as those for use in shipping and protecting jewelry, money or the like valuable and compact objects and articles;—as well as of value and utility in connection with the largest packing cases. The invention is especially applicable for average sized box construction and shipping packages, and it is for this purpose that it is primarily intended to be used.

Referring to the drawings, I have illustrated in Figs. 1 and 2, a typical box construction for packing cases, wherein the sides of the box—of usual board or plank construction—are indicated at 2, 2, the bottom at 1, ends 3 and the top or cover at 4. To the interior of the box I apply one or more inside metal straps, indicated at 10, 10, 10, and I secure these internal reinforcing, strengthening and safety straps to the planking comprising the sides and bottom, as well as the top. Preferably I attach these inside straps by means of staples 12, spanning the edges of adjacent planks and clinch the out-turned points of the staples as clearly shown in Figs. 3 and 4. This can be readily accomplished by perforating the metal strips 10 and driving through the staples of suitable length, width and strength for the particular box construction being built, clinching the points against suitable iron for this purpose. I may also attach each plank to the inside reenforcing strips 10 by ordinary nails 14. I prefer however to utilize the staples, either in connection with the nails 14 or independently for the very important reason that it is possible to drive out by endwise hammering a single plank when only retained by nails 14. Such a plank thus driven out gives access to the interior of the box or packing case, permits pilfering and then when the plank is replaced no indication is left of the fact that the box has been tampered with. But my use of a secure fastening device, however, such for example as the staples 12, either independently or in connection with the ordinary nail fastenings, it is impossible to thus drive out or remove a single plank without entirely destroying the same, splintering and splitting each edge portion where thus secured by the staples 12, and when thus removed it cannot of course be replaced. Consequently the fact of the destruction of the box and access thereto would be discovered instantly, as much so as if the box were broken up entirely with an axe.

I believe that the use of such internal straps with a safety fastening device is distinctly new and this is one of the features of my invention which I have claimed broadly herein.

With the inside strap or straps thus secured to sides, bottom and cover, the edge-most plank of the cover is slotted, as shown at 15. Preferably such slot is made closely adjacent the endmost part of the reinforcing strap 10 at this edge of the cover, the strap being slightly angled or staggered as it is applied to the box and sides, so that the opposite end—which is left projecting above the edge of the side 2—may be fitted through said slot 15 as the cover 4 is closed and placed in position. This step is clearly shown in Figs. 3 and 4.

With the strap 10 thus extending through the top and the cover closed firmly in position, I then drive through a retaining nail 16. Preferably this is a headless or substantially headless nail and is countersunk so as to render the same extremely difficult of removal. This nail perforates the strap 10, said nail being driven substantially midway of the length of the slot 15, and thereby securing the benefit of a firm bearing in the wood at each side of the slot, thus securely holding the strap 10 in place. This construction also results in a firm, rigid and safety locking arrangement.

With the strap or straps 10 thus projecting above the cover, and through the openings 15, provided therefor, the projecting end of each strap is then brought or hammered downwardly over and across the remaining edge of the cover to the position shown in Fig. 5. At this time or previously a similar slot 18 is formed through the topmost edge of the side plank 2, as also clearly illustrated in Fig. 6. I then bend the extreme end part of the projecting strap 10 at an appropriate point so that the same may be brought bent or hammered down snugly around the corner and into the slot 18, and with the endmost portion designated at 20 fitting into said slot 18, thus also effectually closing, concealing and protecting the nail 16. This construction as thus far described, results in a protecting and enclosing reenforcing and locking means at the corner or edge of the box where the strap 10 is thus brought over and greatly strengthens the box construction. This step or method of having an internal reenforcing strap, extending the same through a portion of the box and also reenforcing and protecting the outside and at a corner or edge is also believed to be broadly new, and is herein claimed. In addition to the concealed fastening 16 as thus far described, I add a further retaining or locking member, viz., the nail 21. In driving in this nail I set the same at an angle just clear of the topmost portion of the strap

10 on the cover 4 and so positioned and directed that it will perforate the inturned flange 20 fitting in the slot 18 in the top-most board of the side 2. This nail 21 may 5 also be headless or substantially headless, so that it is extremely difficult to remove the same. Thus a safety reenforcing and locking construction is provided. But in order to still further conceal and protect the safety 10 sealing arrangement thus described, I prefer to drive down an ordinary headed nail 22, closely adjacent the slanting nail 21, which nail 22 will be so positioned as to conceal the fact of any nail 21 whatever. An ordinary 15 observer will at once think that the nail 21 is simply to retain the box cover in position, as is usual, and from an exterior inspection it is substantially impossible to understand just how the overlapping end portions 10 20 are arranged, fitted, fastened or secured, and any intended thieving or pilfering is thus effectively baffled.

In fact I find it is necessary to send instructions with my improved box construction 25 so that the consignee can properly open the box without totally destroying the same.

In order to easily, effectively and expeditiously perforate the straps 10 for insertion of the staples 12 as also to form the recesses 30 15 and 18, I may utilize any suitable or appropriate tool. As illustrated in Fig. 10, a simple form of tool 25 is provided wherein the spaced prongs 26 at one end may be used to perforate the strap or straps 10 where 35 desired, the opposite portion 28 being turned at right angles thereto and providing a surface to receive the blows of a hammer. I also sharpen the end of the flange 28 as indicated at 30, this flange being of suitable 40 width, depth and thickness to form the recesses 15 and 18, a single blow of a hammer being sufficient to effect this perforation of the wood.

With the internal strap construction as 45 thus explained I may, of course, utilize the external straps 35, 35, nailing the same into position around the box as is usual. As a matter of fact these external straps may be entirely dispensed with, owing to the strong 50 protective arrangement of my internal straps, but for large packing cases and for great distances of travel I prefer to apply the outer straps which also tend to conceal 55 the fact of the inner strap construction.

It will thus be seen that I have provided 60 a simple, novel and effective method of box construction and utilizing a reenforcing, protecting and safety sealing arrangement not only serving to indicate if the seal is 65 tampered with, but of such form and strength itself as to prevent tampering with the box or breaking of the seal. My reenforcing, strengthening and sealing device furthermore actually protects the edges or 70 corners and could be, if desired, made to

protect each corner entirely around the box, utilizing separate straps for each side, the bottom and the cover, as will be readily appreciated.

Furthermore, by my method of internal 70 reenforcing straps and staples, I effectually prevent driving out or displacing of one or more boards or planks from a case, and thus eliminate this from the usual methods of damage, tampering and pilfering from 75 boxes. The advantages of my invention, substantially insuring safety in transportation, eliminating insurance costs, difficulties, disputes and claims between consignors and 80 consignees, and the like, are of great importance in commercial use.

My invention is further described and defined in the form of claims as follows:

1. The improved method of box construction which consists in extending a reenforcing metallic strap through a portion of the box, adjacent a corner, bending said metallic strap around the edge of the box and securing said strap on both the interior and exterior of the box. 90

2. The improved method of box construction which consists in extending a reenforcing metallic strap through a portion of the box, adjacent a corner, bending said metallic strap around the edge of the box and securing said strap on both the interior and exterior of the box, and attaching the end by a concealed fastening. 95

3. The improved method of box construction which consists in extending a reenforcing metallic strap through a portion of the box, adjacent a corner, bending said metallic strap around the edge of the box, and securing said strap on both the interior and exterior of the box, and attaching the end by a plurality of concealed fastenings. 100

4. A box construction of the kind described, having an internally positioned reenforcing metal strap, and means attaching said strap to adjacent edges of abutting planks in the box. 110

5. A box construction of the kind described, having an internally positioned reenforcing metal strap, and means attaching said strap to the interior of the planks of the box, one end of said strap extending through the top or cover of the box and means securing said strap to the outside portions of the box. 115

6. A box construction of the kind described, having an internally positioned reenforcing metal strap, means attaching said strap to the interior of the planks of the box, one end of said strap extending through the top or cover of the box adjacent a corner, 125 said strap being bent around the said corner, concealing the end of said strap and means for securing the same.

7. A box construction of the kind described, having an internally positioned re- 130

enforcing metal strap, and means attaching said strap to the interior of the planks of the box, one end of said strap extending through the top or cover of the box adjacent a corner, 5 said strap being bent around the said corner, concealing the end of said strap and a plurality of concealed fastenings securing the same.

8. A box construction of the kind described, having an internally positioned reinforcing metal strap, and means attaching said strap to the interior of the planks of the box, one end of said strap extending through the top or cover of the box adjacent a corner, 10 said strap being bent around 15

the said corner, concealing the end of said strap, and means securing the same comprising one fastening extending through the strap where it passes through the top or cover and a second fastening securing the end of the strap where concealed. 20

9. Box construction having a reinforcing strap, a recess through a portion of said box, an extending end of the strap passing 25 through said recess, and retaining means to hold the strap passing through a portion thereof in said recess.

In testimony whereof, I have signed my name to this specification.

BENJAMIN HOWARD DAVIS.
